UNITED STATES PATENT OFFICE.

GEORGE M. LANE, OF BROOKLYN, NEW YORK.

CAR-SIGNAL.

SPECIFICATION forming part of Letters Patent No. 752,081, dated February 16, 1904.

Application filed May 14, 1903. Serial No. 157,188. (No model.)

To all whom it may concern:

Be it known that I, GEORGE M. LANE, a citizen of the United States, residing at Brooklyn, in the county of Kings and State of New York, have invented certain new and useful Improvements in Car-Signals, of which the following is a specification.

The primary object of this invention is to reduce and minimize the casualties resulting from inattention to signals in railroading and to provide a system in which the engineer is not only admonished of impending danger, but the emergency-brakes automatically set should the engineer neglect to apply same.

In accordance with this invention a signal is located at every dangerous point in the line of a railway and an electric circuit provided for cooperation with the signal to be closed at one point thereby, the locomotive being provided with a signal-circuit forming a part of the circuit located at the danger-point and adapted to be closed by suitable circuit-closing means when the train is passing by the danger-point, so as to advise the engineer of danger ahead. A local circuit applied to the locomotive is controlled by the signal-circuit to effect actuation of the emergency-brake-setting lever even though the engineer should neglect or from other cause fail to apply the brakes when the danger-signal is set.

For a full description of the invention and the merits thereof and also to acquire a knowledge of the details of construction of the means for effecting the result reference is to be had to the following description and drawings hereto attached.

While the essential and characteristic features of the invention are susceptible of modification, still the preferred embodiment of the invention is illustrated in the accompanying drawings, in which—

Figure 1 is a detail view of the invention in operative relation, the same being illustrated in connection with the rear portion of a locomotive and a section of railway-track. Fig. 2 is a detail perspective view of the operating parts applied to the cab of the locomotive and cooperating with the emergency-brake lever. Fig. 3 is a detail view of a section of railway-track, showing the portion of the signal-cir-

cuit applied thereto. Fig. 4 is a detail view of the release mechanism for controlling the circuit-closer of the emergency-brake-setting means. Fig. 5 is a detail view of the contacts for connecting the parts of the signal-circuit applied to the locomotive and railway-track. Fig. 6 is a side view of the swinging contacts applied to the locomotive.

Corresponding and like parts are referred to in the following description and indicated in all the views of the drawings by the same reference characters.

The signal applied to the locomotive or other part of the train may be of any type, either visual or audible. As shown, it consists of an electric lamp 1. Conducting-wires 2 and 3 extend from lamp 1 and are electrically connected with pivoted or swinging contacts 4 and 5, pendent from the locomotive or other part of the train to which the signal may be applied. Contacts 4 and 5 may be of any construction and are pivotally mounted, so as to yield and prevent injury thereto when meeting an obstruction or the fixed contacts applied to the road-bed of the railway-track. For convenience of illustration swinging contacts 4 and 5 are illustrated as mounted upon rod 6, supported by one or more brackets 7, attached to the truck or other convenient part of the locomotive. One of the contacts, as 5, is electrically insulated from rod 6 by sleeve 8, of insulating material.

A part of the signal-circuit is applied to the locomotive, and another part is applied to the railway-track and point adjacent thereto and comprises conductors 9 and 10, battery 11, contacts 12 and 13, and other contacts 14 and 15. A signal 16 of the semaphore type is located at the point along the railway to indicate "danger," and the movable arm 17 thereof is adapted to make electrical connection with contacts 12 and 13 and close the signal-circuit at this point. When the electrical conductors 9 and 10 are closed by electrically connecting contacts 12 and 13, as indicated by the dotted lines in Fig. 3, the signal-circuit is nevertheless open at the contacts 14 and 15 and is not closed until the train reaches this point and contacts 4 and 5 make electrical connection with contacts 14 and 15. When this takes

place, the signal applied to the locomotive or train is operated and the engineer apprised of danger. For a purpose presently to be explained a series of pairs of electric contacts 5 18, 19, 20, and 21 are connected to electric conductors 9 and 10 by means of branch conductors 22, 23, 24, and 25.

The usual emergency-brake-setting lever is indicated at 26, and for automatic operation thereof the following means have been devised: Lever 27 is fulcrumed at 28 intermediate of its ends and is provided with weight 29 or like operating means, link 30, pivoted to lever 27, being constructed to engage with lever 26, so 15 as to throw the latter forward when lever 27 is released from catch 31 or other restraining means. Electromagnet 32 is included in a local circuit comprising wires 33 and 34 and battery 35.

20 36 and 37 indicate the terminals of the local circuit, which are adapted to be electrically connected for energizing electromagnet 32, whereby catch 31 is attracted and operating lever 27 released, so as to automatically throw 25 lever 26 and set the brakes.

An electrically-controlled release mechanism is included in the signal-circuit applied to the locomotive and comprises electromagnet 38, catch 39, spring-actuated disk 40, and 30 circuit-closing arm 41, attached to part 40 and adapted when released to bring contacts 36 and 37 into engagement. Disk or plate 40 is provided with a series of notches 42, corresponding in number to the series of pairs of electric contacts applied to the road-bed of 35 the railway. Notches 42 constitute stops for coöperation with catch 39, whereby circuit-closing arm 41 is held away from contacts 36 and 37. Spring 43 normally tends to rotate 40 plate or disk 40, so as to bring arm 41 in position to press contacts 36 and 37 into engagement, so as to close the local circuit including 45 electromagnet 32. Spring 43 is of the spiral type, one end being attached to plate or disk 40 and the other end being connected to part 44, which may be a bracket or other fixed part of the frame. When the signal-circuit is closed by contacts 4 and 5 sweeping over contacts 18 and 19, electromagnet 38 is energized and attracts catch 39, thereby permitting 50 plate or disk 40 to move forward one step. When the signal-circuit is closed a second time by contacts 4 and 5 sweeping over contacts 14 and 15, electromagnet 38 is a second time energized and attracts catch 39, thereby permitting part 40 to move forward a second step. When the signal is operated a third time by contacts 4 and 5 sweeping over contacts 20 21, electromagnet 28 is a third 55 time energized and attracts catch 39, thereby liberating part 40, which turns under the action of spring 43, so as to throw arm 41 around and effect closing of contacts 36 and 37, whereby the local circuit is closed and 60 electromagnet 32 energized and catch 31 at-

tracted and operating-lever 27 released and emergency-brake-setting lever 26 automatically operated to set the brakes. The number of stops applied to part 40 will depend upon the number of contacts in the series applied 70 to the railway-track, thereby affording opportunity for the vigilant engineer to set the brakes at the first intimation of danger; but should the brakes not be applied by the engineer the automatic actuating means will be 75 brought into play independent of the engineer, so as to set the brakes.

The contacts 4 and 5, applied to the locomotive, are pivotally mounted and are provided with cross-arms 45, which are connected by 80 springs 46 to a part of the engine-frame, whereby said swinging contacts are held perpendicular and in position to make electrical connection with the track-contacts whether the locomotive is advancing or backing, said 85 contacts 4 and 5 being free to move or yield in either direction.

Having thus described the invention, what is claimed as new is—

1. In combination, means for checking the 90 speed of a moving train, automatic actuating means therefor, a restraining device for normally holding the said automatic actuating means out of action, a local circuit applied to the train and including an electromagnet for 95 liberating the said restraining device, means for controlling the said local circuit to liberate the aforementioned restraining device, and operating means for imparting a step-by-step motion to the said local-circuit-controlling 100 means, substantially as specified.

2. In combination, means for checking the speed of a moving train, automatic actuating means therefor, a restraining device for normally holding the said automatic actuating 105 means out of action, a local circuit applied to the train and including an electromagnet for liberating the said restraining device, means for controlling the said local circuit to liberate the aforementioned restraining device, an 110 electric circuit including an electromagnet arranged to operate the said local-circuit-controlling means, and circuit-governing means along the track for effecting successive makes and breaks of the said electric circuit to cause 115 the local-circuit-closing means to receive a step-by-step motion, substantially as specified.

3. In combination, means for checking the speed of a moving train, automatic actuating means therefor, a restraining device for normally holding the said automatic actuating 120 means out of action, a local circuit applied to the train and including an electromagnet for liberating the said restraining device, a spring-actuated arm for controlling the said local 125 circuit to liberate the aforementioned restraining device, a notched plate and catch for retarding the forward movement of the spring-actuated arm, an electric circuit including a signal and an electromagnet, the latter ar- 130

ranged to effect operation of the catch, and means along the track for effecting successive makes and breaks of the electric circuit to simultaneously operate the signal and the catch in consonance with the makes and breaks of the circuit, substantially as and for the purpose specified.

In testimony whereof I affix my signature in presence of two witnesses.
